United States Patent Office.

MATTHEW THORNTON, OF MACON, GEORGIA.

Letters Patent No. 78,244, dated May 26, 1868.

IMPROVED JOURNAL-BOX FOR RAILROAD-CARS.

The Schedule referred to in these Letters Patent and making part of the same.

TO ALL WHOM IT MAY CONCERN:

Be it known that I, MATTHEW THORNTON, of Macon, in the county of Bibb, and State of Georgia, have invented certain new and useful Improvements in Journal-Boxes for Railroad-Cars, &c.; and I do hereby declare the following to be a full, clear, and exact description of the same, reference being had to the accompanying drawings, making a part of this specification, in which—

Figure 1 represents, in perspective, so much of a journal-box as will illustrate my invention.

Figures 2 and 3 represent sections through the same.

Similar letters of reference, where they occur in the separate figures, denote like parts in all of the drawings.

My invention relates to the manner of packing a railroad-car journal-box, for the purpose of keeping the oil in the box, and the dust, dirt, or grit out of it.

To enable those skilled in the art to make and use my invention, I will proceed to describe the same with reference to the drawings.

A represents the top, bottom, and sides of a journal-box, of any usual form or construction, and B represents a car-axle, the journal, C, of which is supported and turns therein. D is the usual "brass" or bearing-block, and E the wedge or key for holding it in proper place or position.

Behind the journal C there is a divided or sectional collar or ring, F, which snugly fits around the axle B, and below the lower half or section of this collar F there is a hemp or other fibrous packing, G, and underneath this packing there is a gland or follower, H, that is brought up against this packing by screw-bolts I I, passing through the flanges J K, one on the journal-box, and the other on the gland or follower. The heads of the screw-bolts, as seen in fig. 1, are so formed as that one side of them shall bear against the journal-box, and thus prevent them from turning when the nuts a a' are turned. Around the shanks of the screw-bolts I, and between their heads and the flange J, a coiled wire or other spring, c, may be placed. But these springs are not positively necessary, as the flexibility and elasticity of the packing, G, acts, to a great extent, as a spring. The under nut, a', is used as a jam-nut, to prevent the other one, a, from working loose.

The upper section of the collar F will always bear against or be close to the axle. Whenever the under section, by wear or otherwise, is not in close proximity to the axle, the gland is drawn up by the screw-bolts against the packing, and the latter is forced against the under section, and thus the joints, where oil might waste, or dust enter, are kept closely packed. The form of the packing admits of its being elongated by pressure upward against it, and a single packing will thus last a very long time, as there is no frictional wear upon it, though it compensates for the wear upon the collar.

Having thus fully described the object and purpose of my invention, what I claim therein as new, and desire to secure by Letters Patent, is—

The packing of a journal-box by means of the divided collar, the fibrous packing, and the gland, arranged to operate in conjunction with the axle, substantially in the manner and for the purpose described.

MATTHEW THORNTON.
